SCRAPER

Arthur Terry Fletcher, Bristol, Conn.

Application December 18, 1939, Serial No. 309,737

14 Claims. (Cl. 30—171)

My invention relates to scrapers.

It has among its objects to provide an improved scraper construction especially adapted to use in scraping floors or the like. A further object is to provide such an improved scraper having improved means for clamping and releasing the scraper blade in the body of the scraper, and, more particularly, such improved means located in an improved position wholly on the scraping end of the scraper. A still further object of my invention is to provide such improved means including an improved rotatable operating member conveniently operated by the user of the scraper and so disposed and associated with cooperating blade clamping means as to markedly reduce the cost of the construction and to be adapted to use with scrapers having handles of any desired length without increasing the cost thereof. These and other objects and advantages of my improved construction will, however, hereinafter more fully appear.

In the accompanying drawing, I have shown for purposes of illustration one embodiment which my invention may assume in practice.

In the drawing:

Figure 1 is a side elevation of a scraper constructed in accordance with my improvement;

Fig. 2 is a bottom plan view of the working end of the same;

Fig. 3 is an enlarged bottom plan view, the holder being broken away and other parts being shown in section, to facilitate illustration;

Fig. 4 is a sectional view on line 4—4 of Figure 3, and

Fig. 5 is an exploded view of the various parts.

In this illustrative construction, I have shown my invention applied to use in connection with a scraper having a long handle 1 and an integral substantially flat body 2 carrying a scraper blade 3 along its front edge and an angularly disposed clamping portion 4 pressing the blade against the sloping front end 5 of the scraper body 2; this clamping portion 4 being connected to the body 2 and clamped against the same by improved means hereinafter described.

Herein, these means include an improved rearwardly directed portion on the clamping portion 4 and receivable in a usual longitudinally directed horizontally disposed slot 6 in the front end of the body 2, and further include improved clamping connections between this rearwardly extending portion, generally indicated at 7, and an improved rotatable clamping member 8. More particularly, this clamping member 8 is carried in a suitable transverse recess 9 cen-

trally located in the body 2, and this member 8 projects through this recess beyond the top and bottom of this body portion. This rotatable member 8, as herein, is also preferably knurled on its periphery, as shown at 10. Further, it will be observed that it is internally threaded, as at 11, and adapted to cooperate with corresponding threaded edge portions 12 on a flat central extension 13 on the rearwardly directed portion 8. It will further be noted that the threaded end of this portion 13 extends rearwardly beyond the remainder of the portion 7, and that cut-outs or openings 14 are provided between the opposite sides of the base of this portion 13 and the spaced outer parts of the portion 7. Moreover, it will be observed that a washer 15 is also disposed in the aperture 9 between the rotatable member 8 and the front wall 16 of the recess 9, and that the slot 6 extends back of the aperture 9 sufficiently to permit the extremity of the portion 13 to move freely in this slot without engagement with the back wall 17 thereof.

In the use of my improved construction, it will be evident that the rotatable member 8 may be readily adjusted by engagement of the operator's fingers with either, or both, top or bottom exposed portions of member 8, to clamp or release the blade 3 between the clamping portion 4 and the inclined front end portion 5 on the body 2. Thus, whenever it is desired to change the scraper blade 3, it is only necessary to release the member 8 by rotating the same in one direction sufficiently to effect the necessary longitudinal movement of the extension 13 to release the clamping portion 4 and permit the blade 3 to be withdrawn; while a reverse rotation of the member 8 will obviously securely clamp the blade by effecting a reverse longitudinal movement of the extension 13. In the use of the scraper, it will also be evident that the member 8 is so disposed in the upper surface of the body 2 of the scraper as in no way to interfere with the normal use of the scraper, while providing in rear of the member 8 an ample area for engagement of the palm of the hand with the body of the scraper.

As a result of my improved construction, it is made possible, while utilizing a centrally located clamping connection, to maintain the scraper blade securely in position, while requiring only a single clamping means. Moreover, while utilizing such a single clamping connection, it is made possible to utilize improved controlling means adapted to be manipulated by the fingers without requiring the use of any tools, and fur-

ther to dispose these improved means in such an improved location that there are no irregularities in the surface of the body portion of the scraper pressed down upon by the operator which are apt to produce injury to the hands during continued use of the structure. Further, the structure required is exceedingly simple and inexpensive, all boring or cutting in rear of the slot being eliminated, while the longitudinally movable clamping member and the cooperating rotatable member are also inexpensively provided and adapted to be used without change irrespective of variations in the length of the handle 1. Attention is also directed to the fact that the central location of the threaded portion on the rearwardly extending clamping member and its cooperation with the rotatable clamping member, is such as to insure alignment of the longitudinally adjustable clamping member and ready tightening or release of the same without objectionable weakening of the holder, and while producing a construction which is adapted to have long life in service. These and other advantages of my improved construction will, however, be clearly apparent to those skilled in the art.

While I have herein specifically described one embodiment which my invention may assume in practice, it will be understood that the same has been shown for purposes of illustration, and that my invention may be modified and embodied in other forms without departing from its spirit or the scope of the appended claims.

What I claim as new and desire to secure by Letters Patent is:

1. In a scraper, a scraper body having a front clamping edge, a blade clamping member thereon and adapted to clamp a blade along said edge, and cooperating means intermediate the ends of said body and on said body and clamping member for moving said clamping member longitudinally of said body and tightening and releasing said clamping member.

2. In a scraper, a scraper body, a blade clamping member thereon, and cooperating means centrally located on said body and clamping member for moving said clamping member reversely longitudinally of said body and tightening and releasing said clamping member, including a centrally located clamp operating member intermediate the ends of said body.

3. In a scraper, a scraper body having a transverse aperture therein, a blade clamping member thereon, and cooperating means centrally located on said body and clamping member for tightening and releasing said clamping member longitudinally of said body, including a centrally located rotatable clamp operating member rotatable in said aperture and threaded on said clamping member.

4. In a scraper, a scraper body having transverse aperture means therein, a blade clamping member thereon, and cooperating means on said body and clamping member for tightening and releasing said clamping member longitudinally of said body, including rotatable clamp operating means rotatable in said aperture means and threaded on said clamping member and having finger operated operating means engageable from opposite surfaces of said body.

5. In a scraper, a scraper body, a blade clamping member thereon, and cooperating means centrally located on said body and clamping member for tightening and releasing said clamping member, including a rearwardly extending

threaded portion on said clamping member terminating intermediate the ends of said body and a cooperating rotatable clamping member on said body intermediate the ends thereof and threaded on said portion and rotatable to clamp or release said clamping member.

6. In a scraper, a scraper body, a blade clamping member thereon, and cooperating means centrally located on said body and clamping member for tightening and releasing said clamping member, including a centrally located threaded portion on said clamping member and a cooperating rotatable clamping member on said body rotatable to clamp or release said clamping member, said body having a longitudinal slot receiving said first mentioned clamping member and also a relatively transverse aperture in which said rotatable clamping member is rotatable.

7. In a scraper, a scraper body, a blade clamping member thereon, and cooperating means centrally located on said body and clamping member for tightening and releasing said clamping member, including a centrally located threaded portion on said clamping member and a cooperating rotatable clamping member on said body rotatable to clamp or release said clamping member, said body having a longitudinal slot receiving said first mentioned clamping member and also a relatively transverse aperture extending across the inner end of said longitudinal slot and in which said rotatable clamping member is rotatable, and said rotatable clamping member having a peripheral actuating portion engageable through said aperture.

8. In a scraper, a scraper body, a blade clamping member thereon, and cooperating means centrally located on said body and clamping member for tightening and releasing said clamping member, including a centrally located threaded portion on said clamping member and a cooperating rotatable clamping member on said body rotatable to clamp or release said clamping member, said body having a longitudinal slot receiving said first mentioned clamping member and also a transverse aperture in which said rotatable clamping member is rotatable, said longitudinal slot being substantially midway between the top and bottom of said body portion and said rotatable member having peripheral portions engageable through the top and bottom of said transverse aperture.

9. In a scraper, a longitudinally slotted and transversely apertured scraper body, a clamping member having a rearwardly extended portion received in the longitudinally extending slot in said body and a centrally located rearwardly projecting threaded portion, and a rotatable actuating member disposed in the transverse aperture in said body and threaded on said threaded portion.

10. In a scraper, a longitudinally slotted and transversely apertured scraper body, a clamping member having a rearwardly extended portion received in the longitudinally extending slot therein and a centrally located rearwardly projecting threaded portion, and a rotatable actuating member disposed in the transverse aperture in said body and threaded on said threaded portion, said clamping member having plate portions on opposite sides of said threaded portion laterally spaced from the latter.

11. In a scraper, a longitudinally slotted and transversely apertured scraper body, a clamping member having a rearwardly extended portion received in the longitudinally extending slot

therein and a centrally located rearwardly projecting threaded portion, and a rotatable actuating member disposed in the transverse aperture in said body and threaded on said threaded portion, said clamping member having a plate portion extending into said longitudinally extending slot and said threaded portion thereon comprising oppositely threaded edges of a central tongue on said plate portion.

12. In a scraper, a longitudinally slotted and transversely apertured scraper body, a clamping member having a rearwardly extended portion received in the longitudinally extending slot therein and a centrally located rearwardly projecting threaded portion, a rotatable actuating member disposed in the transverse aperture in said body and threaded on said threaded portion, and a washer surrounding said rearwardly extended portion and providing an abutment between said rotatable member and the wall of the transverse aperture toward said clamping member. 10 15 20

13. A clamping member for scrapers including a rearwardly extending plate portion having on one end thereof a central flat tongue threaded on its opposite edges, an angularly disposed blade engaging portion on the opposite end of said plate portion, and said plate portion extending laterally between its ends to the opposite ends of said blade engaging portion.

14. A clamping member for scrapers including a rearwardly extending plate portion having on one end thereof a central flat tongue threaded on its opposite edges adjacent its extremity, an angularly disposed blade engaging portion on the opposite end of said plate portion, and said plate portion having extensions adjacent the opposite ends of said blade engaging portion spaced laterally from said flat central tongue, and a rotatable externally roughened actuating member threaded on said tongue.

ARTHUR TERRY FLETCHER.
